DESIGN FOR A DISPLAY REEL FOR STRIP MATERIAL

Otto A. Boesel, Ansonia, Conn., assignor to The H. A. Matthews Manufacturing Company, Seymour, Conn., a Corporation

Application June 14, 1933. Serial No. 48,396

Term of patent 7 years

To all whom it may concern:

Be it known that I, Otto A. BOESEL, a citizen of the United States, residing at Ansonia, in the county of New Haven and State of Connecticut, have invented a new, original, and ornamental Design for a Display Reel for Strip Material, of which the following is a specification, reference being had to the accompanying drawing, forming part thereof.

Fig. 1 is a perspective view of a display reel for strip material showing my new design; and Fig. 2 is a face view of one end thereof.

I claim:

The ornamental design for a display reel for strip material as shown.

OTTO A. BOESEL.
